UNITED STATES PATENT OFFICE.

GEORGE ERNSHAW GARRETSON, OF RUSSELLVILLE, KENTUCKY.

RUNNING-GEAR FOR VEHICLES.

SPECIFICATION forming part of Letters Patent No. 328,933, dated October 27, 1885.

Application filed August 3, 1885. Serial No. 173,454. (No model.)

To all whom it may concern:

Be it known that I, GEORGE E. GARRETSON, a citizen of the United States, residing at Russellville, in the county of Logan and State of Kentucky, have invented a new and useful Improvement in Running-Gear for Vehicles, of which the following is a specification, reference being had to the accompanying drawings.

My invention has relation to improvements in running-gear for vehicles, especially adapted for use in connection with buggies or light wagons; and the novelty consists in the peculiar construction, combination, and arrangement of the various parts for service, substantially as hereinafter fully set forth, and particularly pointed out in the claims.

The object of my invention is to combine simplicity, durability, and strength of construction in a running-gear for vehicles of the side-bar class with cheapness of manufacture, capability of ready detachment of the various parts for repairing, and the necessary resiliency of the springs when traveling on rough roads or streets.

In the drawings hereto annexed, Figure 1 is a top plan view of a running-gear embodying my invention. Fig. 2 is a side elevation thereof. Fig. 3 is a bottom plan view. Fig. 4 is a detached detail view of the head-block or plate of the front axle, showing the means for pivoting the said axle and connecting the perch or reach and springs thereto. Fig. 5 is a detached detail view of the manner in which the rear end of the perch or reach and springs are connected to the rear axle. Fig. 6 is a detailed sectional view of the front end of the reach or perch and axle, showing the means for permitting the reach or perch to slide or recede under a heavy pressure on the springs.

Like letters of reference indicate like parts in all the figures of the drawings.

Referring to the drawings, A A' designate the front and rear axles respectively, connected together by a perch or pole, B, as will be more fully described presently, the rear axle, A', being arranged on a plane slightly above the plane of the front axle, and braced against lateral play or displacement by side braces, C C, which are bolted or otherwise connected at their front ends to opposite sides of the perch-pole at about the middle thereof,

and at their rear ends said braces are secured or bolted to the rear axle, A', by means of clips or bolts, a brace being arranged on each side of the perch-pole and connected thereto and to the outer ends of the said axle, as described.

D D designate the springs, of any preferred construction, said springs being arranged on each side of the perch-pole B, at a short distance therefrom, and running nearly parallel therewith, the springs herein shown having each an upwardly-curved central portion, d d, arranged considerably above the plane of the perch-pole and axles. The front and rear ends of each spring D are located below the plane of the curved portion d thereof, and extend under the axles A A', where they are pivoted to or bent around plates or head-blocks E F, secured to the front and rear axles, respectively, as presently described, and on the under or lower surfaces thereof.

The head-block E comprises a body portion, e, curved as shown, side arms e', a front projecting lug, e'', and a rear projecting plate, e'', all of said parts being formed integral with each other and constituting a single casting for lightness and strength and simplicity. The body e has a central aperture or opening therein for the passage of a king-bolt, E', having a nut, E'', which bears against the lower surface of the body e, said bolt E' serving as the pivot on which the front axle turns.

The bolt E' passes through the body e, the axle, a bearing-plate, E'', secured on the upper face of the axle by means of bolts passed through side arms E' thereof, and an upper bearing-plate, E'', adapted to bear on its lower surface on the plate E'', and receive on its upper surface the head of the king-bolt E'. The plate E'' has projecting ears or lugs h h, arranged parallel with the lug e'' and plate e'' of the head-block E, said lugs h h being perforated for the passage of securing-bolts h' h', the upper headed ends of which bear on the lugs h h, while the lower screw-threaded ends thereof are passed through apertures formed in the lug e'' and plate e'' for their reception, and receive securing-nuts h'' h'', which bear on the lower surface of said lug e'' and plate e'', thus securely and firmly connecting the several parts together, while permitting of the axle turning thereon in the movements required to turn

corners or angles. The outer ends of the side arms e' , to which the front ends of the springs D are connected, are cut away to provide a pin or bearing, around which the ends of the 5 springs may be bent or pivoted, so as to lie flush with the upper surface of the remaining portion of the arms e' , the springs being prevented from becoming disengaged or misplaced laterally by means of nuts e' , fitted or screwed 10 on the screw-threaded pin or bearing of the arms e' , thus providing a simple, strong, and efficient connection for the front ends of the springs D.

The rearwardly-projecting plate e^3 is of considerable length, and fits against the lower surface of the reach or perch-pole B. This plate extends to a point at or near the middle of the perch-pole to provide a large area of bearing-surface therefor.

20 The reach is free to slide or recede from the front axle when any undue strain or weight comes upon the springs D D, said reach being provided with downwardly-projecting bolts i , which pass therethrough and work in longitudinal slots $i' i'$, formed in the plate e^3 , near the ends thereof, a packing or filling of leather or any other suitable material, I, being arranged between the meeting surfaces of the reach and plate to "deaden" the noise incident upon the movement of the bearing-surfaces of the reach and plate.

The rear plate, F, is of a greater length than the head-block E, and is secured upon the lower surface of the rear axle at the middle 35 thereof by means of clips or bolts F', the outer ends of said plate being bent downwardly, as at f, and having a reduced or cut-away portion to provide a pin or bearing, f', around which the rear ends of the springs D D are 40 bent or pivoted in a manner similar to the front ends thereof, and prevented from becoming disengaged by nuts f^3 , screwed on the screw-threaded outer ends of said pins or bearings f'.

45 The rear end of the perch-pole B terminates a short distance from the rear axle, and is provided with a plate, G, by means of which it is secured to the axle.

The front end of the plate G is connected or 50 secured to the under face of the perch B by means of bolts or clips g, and is provided with a bent or curved portion, g', and at its rear end said plate is clipped or bolted to the under surface of the rear axle, as clearly shown.

55 H H designate longitudinal side bars, arranged above and at one side of each of the springs D D, to which bars the body of vehicle, whether a wagon or buggy, is secured by any proper means—as, for instance, the 60 body may be bolted or clipped in the usual way directly to the bars, or it may have transverse bars at its front and rear ends, which project beyond the sides thereof and are bolted or clipped to said side bars, as is obvious.

65 J J' J² designate transverse supporting or holding bars, arranged about the middle of

the perch, above the same, and extending transversely across the pole, as shown, said bars being bolted or clipped near their outer ends to the elevated curved portion of the 70 side springs, D D, on which they rest and are supported thereby. The middle bar, J, is preferably made straight, while the outer ends of each of the bars J' J² are curved outwardly, as at j, and away from each other, the extreme 75 outer ends of each of the bars J J' J² being reduced or cut away, as at j², and fitting under the side bars, H, to which they are secured by means of bolts or clips k, having securing-nuts k'.

80 Between the lower surface of each of the bars J J' J² and the nuts k' is arranged a plate, L, bent as at l, and secured at its ends to the lower surface of the side bars, H, by bolts or otherwise, a plate being provided for each side 85 bar, as clearly shown.

The side bars are connected together to prevent displacement or play thereof, and add strength thereto, by cross braces or bars M M, one being secured at each side of the bars 90 J J' J² and to the bars H at its opposite ends and on the under surfaces of said bars H by bolts or otherwise.

95 It will be observed that the necessary resiliency is imparted to the body of the vehicle by the movement of the springs, which are pivoted at their ends, as described, to allow the middle curved portions to give to a greater degree and allow a greater range of movement thereof without affecting the perch-pole; but 100 when any undue weight or strain is imposed on said springs they are forced down still lower, and the perch-pole is caused to slide upon the plate by being drawn backward by the rear ends of the springs forcing the rear 105 axle backward, thus imposing a portion of the greatest strain upon the perch-pole and relieving the springs from a portion of the weight, the sliding movement of the perch-pole separating the axles to a farther distance 110 apart than their normal position, and allowing a further downward movement of the springs.

A running-gear constructed in accordance 115 with my invention possesses great durability and strength, is simple in construction, efficient in operation, can be readily taken apart for repairing, &c., and by reason of its great simplicity and freedom from complex mechanisms it can be repaired by any ordinary blacksmith or carriage-repairer.

120 The middle portions of each of the supporting-bars J J' J² fit or abut against each other, and are bolted together by a through-bolt, m, having a nut, m'.

I am aware that heretofore it has been proposed to provide a wagon with a tubular portion rigidly secured to the rear axle and extending nearly to the front axle and having limiting-screws, a pole rigidly connected to the fifth-wheel of the front axle and free to slide 125 and rotate in said tubular portion of the rear axle, said pole having limiting recessed por-

tions in which the set-screws work; also, that it is not new to connect the springs pivotally to the axles.

Having thus fully described my invention, 5 what I claim as new, and desire to secure by Letters Patent, is—

1. In a running-gear, the combination of the axles, plates *e* *F*, rigidly bolted to said axles and having reduced supporting-arms, 10 side springs, *D*, pivotally connected to said axle-plates at the reduced ends thereof, a slotted plate, *e*³, formed with the plate *e* of the front axle, a perch-pole, rigidly secured to the rear axle and resting and free to slide upon the 15 slotted plate *e*³, through-bolts *i*, to connect said pole and plate together and limit the movement of the pole, and a packing, *I*, of leather interposed between the pole and plate *e*³, as set forth.
2. In a running-gear, the combination of the axle, side springs arranged parallel with each other, a perch-pole, a head-block, pivotally connected with the axle and having side arms, *e'*, to which the ends of the springs are 25 connected, an upper bearing-plate secured upon the axle, a plate adapted to bear on the upper plate and connected to the head-block, and a king-bolt passing through the bearing-plates, axle, and head-block, substantially as described.

3. In a running-gear, the combination, with the rear axle and the side springs, of a plate bolted to the under side of the axle, and having a bent arm at each side, provided with a bearing for the rear end of one of the said springs, as and for the purpose set forth.

4. In a running-gear, the combination, with the axles, a perch-pole, and the side springs, of a plate secured to the under surface of each axle, and having lateral arms provided with 40 bearings for the ends of the said springs, which are pivotally connected thereto, as set forth.

5. In a running-gear, the combination of the axles, the side springs, a perch-pole rigidly connected at its rear end to the axle and adapted to slide at its front end, a plate secured to the rear axle and having bearings for the rear ends of the springs, and a head-block pivotally secured to the front axle and 45 provided with end bearings for the springs, and a plate having slots adapted to receive the front end of the perch-pole and its securing-bolts, substantially as described.

6. In a running-gear, the combination of 50 the side springs, the transverse supporting-bars bolted together at their middle and to the elevated portions of the side springs, and parallel side bars bolted to the outer ends of the transverse supporting-bars and adapted 55 to support the vehicle-body, substantially as described.

In testimony that I claim the foregoing as my own I have hereto affixed my signature in presence of two witnesses.

GEORGE ERNSHAW GARRETSON.
